King-Seeley Thermos Co.

Filed Apr. 8, 1974, Ser. No. 458,537

Term of patent 14 years

Int. Cl. D3—01; D7—99

U.S. Cl. D7—76

FIG. 1 is a perspective view of combined vacuum bottles, sandwich box, and carrying case therefor showing my new design.

FIG. 2 is a top plan view on an enlarged scale.

FIG. 3 is a front, elevational view on an enlarged scale, the rear view being substantially similar.

FIG. 4 is an end elevational view taken from the right of FIG. 3.

I claim:

The ornamental design for combined vacuum bottles, sandwich box and carrying case therefor, substantially as shown and described.
